UNITED STATES PATENT OFFICE.

THEODORE H. GOODNOW, OF OAK PARK, AND WILLIAM S. SCHROEDER, OF CHICAGO,
ILLINOIS.

RELEASE RIGGING.

Application filed July 21, 1920. Serial No. 397,841.

To all whom it may concern:

Be it known that we, THEODORE H. GOODNOW and WILLIAM S. SCHROEDER, citizens of the United States, residing, respectively, at 5 Oak Park and Chicago, both in the county of Cook and State of Illinois, have invented a new and useful Improvement in Release Rigging, of which the following is a specification.

10 This invention relates to improvements in release rigging and more particularly to the two-lever type of device for uncoupling rail-way cars.

15 It is the object of this invention to provide an uncoupling device of this character in which the pin lever and hand lever are fulcrumed in a bracket, that acts also as a stop for the pin lever should it become broken or detached from the locking pin of 20 the coupler and prevents its flying back and striking the operator. It is a further object of this invention to so construct the bracket as to positively retain the two levers normally at their fulcrum, yet allow of the 25 ready removal or replacement, should it be desired.

30 While the preferred forms of this invention are illustrated upon the accompanying sheets of drawing, yet it is to be understood that detail changes may be made without departing from the scope thereof.

35 In the drawing, Figure 1, is a view in elevation of the end of a car, with parts broken away, illustrating one form of this invention attached to the end sill of the car.

40 Figure 2; is an enlarged detail plan view of the bracket, with the parts of the levers broken off and the end sill in section on the line A—A Figure 1.

45 Figure 3; is an enlarged detail view in side elevation of the bracket, looking in the direction of the arrows on Figure 1, showing the end sill and lever in section on the line B—B of that figure.

50 Figure 4; is an enlarged detail view in front elevation of the bracket with a part of the outer end broken away to show the end of the pin lever.

55 Figure 5; is a top plan view of the end of a car, with parts broken away, illustrating a modified form of this invention attached to the end sill of the car.

60 Figure 6; is an enlarged detail view in front elevation, looking in the direction of the arrow A—A, Figure 5, with the ends

of the lever broken off and a part of the bracket broken away to show the end of the pin lever.

Figure 7; is an enlarged detail view in side elevation of the bracket, looking in the direction of the arrows on Figure 5, with the lever and end sill in section taken on the line B—B.

In the forms of this invention illustrated, 1 represents the end of a freight car with parts broken away, 2 the end sill, 3 the coupler head and 4 the locking pin. One end of the pin lever 5 passes through the eye of the locking pin, or other connection, while the other is normally retained from 65 excessive lateral movement but capable of limited oscillation in a bracket 6 attached to the end sill. The hand lever 7 is also normally retained against excessive lateral movement in the bracket but capable of oscillation and is provided with an arm 8 for actuating the pin lever.

The bracket 6 comprises a base 9 adapted to be secured to the end sill by bolts or other means, with an arm 10 extending at right 70 angles therefrom for mounting and acting as a fulcrum for the hand and pin levers. The top and bottom of the bracket arm at the outer end are provided with extensions or flanges 11 protruding in the direction of 75 the longitudinal center of the car and the body of the arm between the extensions is provided with an aperture or slot 12 of sufficient size to allow the ends of both levers to be passed therethrough. The hand lever is 80 provided with a stud 13 on the side next the end sill adapted to limit the movement of the lever from normal position in a direction away from the coupler head by engaging the bracket arm and the lever body on the other 85 side of the bracket arm is bent or offset to form an integral shoulder 14 adapted to engage the bracket arm and limit the movement of the lever in the opposite direction. The bracket arm aperture 12 is extended on 90 one side to form a continuation 15 of less height than the main aperture and of a width sufficient to receive the end of one lever. The pin lever near its end is cut 95 away on top to form a groove or indentation 16, and is adapted to be received within the continuation of the aperture and when in place the ends of the indentation will engage the bracket wall and limit the movement of the lever in both directions.

To assemble, the hand lever is passed through the bracket arm main aperture until the shoulder 14 and stud 13 are on opposite sides of the bracket wall, the lever 5 then is moved bodily against the wall which allows sufficient space in the main aperture for the insertion of the indented end of the pin lever. When the indentation of the pin lever comes within the bracket arm, this 10 lever is moved bodily within the continuation of the aperture with the indentation under the upper part of the arm body. To maintain the levers in this position a cotter or split pin 17 is passed through the arm 15 extensions 11 and between the ends of the levers thereby holding each in its normal position within the bracket.

It is readily seen that the bracket in both 20 forms shown forms a fulcrum for both levers and should the locking pin engaging end of the pin lever become broken or detached the bracket arm extension will act as a stop and prevent the lever flying back endangering the operator. To remove or 25 replace the levers or one of them, the cotter pin which separates them is removed allowing first one and then the other lever to be moved towards the center of the aperture and out of the engagement with the bracket 30 arm.

Figures 5, 6 and 7 illustrate another form 35 of application of this invention in which the bracket 20 is of the same general construction. The hand lever is also provided with a stud 21 but extends straight throughout its length and is not shouldered. The 40 pin lever is provided with an indentation 22 on its upper side near the end. The aperture in the bracket arm is irregular in form, one portion 23 being of such shape and size 45 as to receive the hand lever and the other portion 24 to receive the pin lever with the ends of the indentation 22 adapted to engage either side of the bracket arm.

To assemble, it is necessary to first insert 50 the end of the pin lever in the larger portion of the aperture and then move it bodily over into normal position which will allow the end of the hand lever to be inserted until the stud engages the bracket arm. To maintain the lever in normal relation to the bracket arm a cotter or split pin 25 is passed transversely through the hand lever on the 55 side of the bracket opposite the coupler and clear of the adjacent end of the pin lever. To remove the lever from the bracket the cotter is removed which allows the removal of the hand lever first which in turn allows the pin lever to be taken out.

In both forms, the levers each have an 60 oscillatory movement in both horizontal and vertical planes within the bracket. The movement in the vertical plane being limited by the top and bottom of the lever within 65 the bracket engaging the bracket arm

body. In the first form the cotter pin separates the adjacent ends of the levers and allows a limited oscillation in a horizontal plane, the movement being limited by the contact of the levers with each other. In 70 the latter form, as the adjacent ends of the levers contact with each other it is necessary to provide a curved contacting surface on one of them to allow the limited oscillation in a horizontal plane, required to prevent the movement of the car from breaking the lever. As shown the indented end of this pin lever is provided with a thickened portion 26 within the bracket which is curved and rounds off to the end on one 80 side of the bracket and tapers into the normal lever on the other side of the bracket.

What we claim is:

1. In a release rigging, the combination 85 with the hand and pin levers of a lever bracket adapted to be secured to the car, the adjacent ends of said levers passing through the bracket and fulcrumed thereon, and means upon each lever co-acting with the bracket for limiting longitudinal movement 90 of the levers.

2. In a release rigging, the combination 95 with the hand and pin levers of a lever bracket adapted to be secured to the car, the adjacent ends of said levers passing through the bracket and fulcrumed thereon, means upon each lever co-acting with the bracket for limiting longitudinal movement of the levers, and means forming parts of the bracket limiting oscillation in a vertical plane.

3. In a release rigging, the combination 105 with the hand and pin levers of a lever bracket adapted to be secured to the car, said bracket including an arm provided with an aperture adapted to receive and mount the adjacent ends of the levers and means upon the bracket co-acting with means upon one lever limiting longitudinal movement of one lever, and means forming parts of the bracket limiting oscillation of both levers.

4. In a release rigging, the combination 115 with the hand and pin levers of a lever bracket adapted to be secured to the car, said bracket including an arm provided with an aperture adapted to receive and mount the adjacent ends of the levers and means upon the bracket co-acting with means upon one lever limiting longitudinal movement of that lever, and means upon the other lever limiting longitudinal movement of that lever.

5. In a release rigging, the combination 125 with the hand and pin levers of a lever bracket adapted to be secured to the car, said bracket including an arm provided with an aperture adapted to receive and mount the adjacent ends of the levers and means upon the bracket co-acting with

- means upon one lever limiting longitudinal movement of that lever, means upon the other lever limiting longitudinal movement of that lever, and means forming parts of 5 the bracket limiting oscillation of both levers in a vertical plane.
6. In a release rigging, the combination with the hand and pin levers of a lever bracket adapted to be secured to the car, 10 said bracket including an arm provided with an aperture adapted to receive the ends of the levers, one lever having an indentation on one edge, said aperture having a continuation of lesser height adapted to receive the 15 indented portion of the lever, and means for maintaining both levers in the bracket.
7. In a release rigging, the combination with the hand and pin levers of a lever bracket adapted to be secured to the car, said 20 bracket including an arm provided with an aperture adapted to receive the ends of the levers, one lever having an indentation on one edge, said aperture having a continuation of lesser height adapted to receive the 25 indented portion of the lever, and limit longitudinal movement of said lever.
8. In a release rigging, the combination with the hand and pin levers of a lever bracket adapted to be secured to the car, said 20 bracket including an arm provided with an aperture adapted to receive the ends of the levers, one lever having an indentation on one edge, said aperture having a continuation of lesser height adapted to receive the 25 indented portion of the lever and limit longitudinal movement of said lever and means for maintaining both levers in the bracket.
9. In a release rigging, the combination 40 with the hand and pin levers of a lever bracket, adapted to be secured to the car, said bracket including an arm provided with an aperture adapted to receive the ends of the levers, one lever having an indentation on one edge, said aperture having a continuation of lesser height adapted to receive the 45 indented portion of the lever and limit longitudinal movement of said lever, means for maintaining both levers in the bracket, and means between the sides of the levers allowing limited oscillation in the horizontal plane.
10. In a release rigging, the combination with the hand and pin levers of a lever bracket adapted to be secured to the car, having an arm provided with an aperture receiving the adjacent ends of the levers, one lever having an indentation on one edge the ends of which form shoulders adapted in normal position to be engaged by the body of the bracket arm upon longitudinal movement of said lever, and means maintaining both levers in normal position within the bracket arm and allowing oscillation of the levers 55 in a horizontal plane.
11. In a release rigging, the combination with the hand and pin levers of a lever bracket adapted to be secured to the car, having an arm provided with an aperture receiving the adjacent ends of the levers, one lever having an indentation on one edge the ends of which form shoulders adapted in normal position to be engaged by the body of the bracket arm upon longitudinal movement of said lever, and means upon the other 60 lever adapted to engage the bracket arm and limit the longitudinal movement of said lever.
12. In a release rigging, the combination with the hand and pin levers of a lever bracket adapted to be secured to the car, having an arm provided with an aperture receiving the adjacent ends of the levers, one lever having an indentation on one edge the ends of which form shoulders adapted in normal position to be engaged by the body of the bracket arm upon longitudinal movement of said lever, and means upon the other lever adapted to engage the bracket arm and limit the longitudinal movement of said 75 lever, and means maintaining both levers in normal position within the bracket arm, said means allowing oscillation of the levers in a horizontal plane.
